UNITED STATES PATENT OFFICE.

JAMES WILKINSON, OF SCHENECTADY, NEW YORK, ASSIGNOR TO GENERAL ELECTRIC COMPANY, A CORPORATION OF NEW YORK.

SHAFT-PACKING.

1,394,959.

Specification of Letters Patent. Patented Oct. 25, 1921.

Application filed May 9, 1919. Serial No. 295,980.

To all whom it may concern:

Be it known that I, JAMES WILKINSON, a citizen of the United States, residing at Schenectady, in the county of Schenectady, 5 State of New York, have invented certain new and useful Improvements in Shaft-Packings, of which the following is a specification.

The present invention relates to packings 10 such as are used to prevent leakage of fluid between two relatively rotating parts. Such packings are used, for example, in connection with rotating shafts to prevent leakage between a shaft and an adjacent wall through 15 which it passes, one well-known application being found in connection with elastic fluid turbines.

The invention relates more particularly to packings of the liquid seal type and has for 20 its object to provide an improved structure in packings of this character.

For a consideration of what I believe to 25 to be novel and my invention, attention is directed to the accompanying description and the claims appended thereto.

In the drawing, Figure 1 is a longitudinal radial sectional view of a packing embodying my invention; Fig. 2 is a section taken on line 2-2, Fig. 1, and Figs. 3 and 4 are 30 views, similar to those of Figs. 1 and 2 respectively, showing another embodiment of my invention.

Referring to the drawing, (Figs. 1 and 2) 5 indicates a rotating shaft and 6 a casing having an opening 7 through which the shaft passes and between which and the shaft it is desired to prevent leakage. Bolted to the casing 6 at opening 7 is a housing comprising an inner end wall 8, an outer end 40 wall 9, and an annular side wall 10, preferably formed integral with walls 8 and 9. In the present instance one-half of wall 10 is formed integral with end wall 8 and the other half is formed integral with wall 9. 45 Walls 8 and 9 are fastened to casing 6 by means of a flanged ring 11 fastened to casing 6 by bolts 11^a. Carried by shaft 5 inside the housing is an impeller 12 having on its opposite sides suitable vanes 13 which are 50 closed by side plates 14. Side plates 14 are fastened to the vanes by means of rivets 15. Impeller 12 has a peripheral rim 16 of the same width as vanes 13 and between rim 16 and the inner wall of the housing is a slight 55 clearance forming annular passages 17 and

18. In annular wall 10 surrounding impeller 12 is a continuous groove 19, and communicating with groove 19 at the upper side thereof is an opening 20 in which is fastened a liquid supply pipe 21. Liquid supply 60 pipe 21 may lead from any suitable source of supply, and supplies liquid to annular groove 19 so there is a complete ring of liquid around the periphery of the impeller. The outer periphery of side plates 14 are cut 65 away to form annular chambers 22 to which impeller 12 when operating delivers liquid, and chambers 22 are in communication with groove 19 through passages 17 and 18 and they are in communication with the spaces 70 between side plates 14 and end walls 8 and 9 through annular clearance spaces 23 and 24. There is considerable clearance between side plates 14 and end walls 8 and 9 and at their 75 radially inner portions such side plates and end walls are provided with interleaving annular rings 25 and 26 respectively, thus forming a labyrinth packing. Impeller 12 is provided with hub extensions 27 on which are cut threads 28 which run in directions 80 to pump any liquid which falls on the shaft back to the impeller. For this purpose one thread will be left hand and the other right hand.

In operation, sealing liquid, such as water, 85 is supplied through pipe 21 to annular groove 19 and from here liquid will be fed to the impeller which acts by centrifugal force to establish a liquid seal to prevent leakage. Assuming for example, that 90 the pressure on the left hand side of the packing is greater than that on the right hand side, then a liquid seal will be established having a static head of a height indicated at *a* depending among other things 95 on the difference in pressure on the two sides of the packing.

The impeller vanes 13 act as a pump taking water at their radially inner or suction ends and delivering it at their radially outer 100 or discharge ends. The water received at the inner ends of the vanes is that which is discharged from the outer ends and flows to the inner ends through the path between side plates 14 walls 8 and 9. This flow, 105 which is in the nature of local circulation, will be greater on the low pressure side of the packing than it is on the high pressure side of the packing.

After the liquid seal is established, how- 110

ever, there will be but little flow from the discharge ends of the impeller to the suction ends due to the arrangement whereby close clearances are provided between the peripheries of rim 16 and side plates 14 on the one hand and casing wall 10 on the other hand; and due also to the labyrinth packing means formed by rings 25 and 26. The foregoing arrangement forms in substance, 10 a means which impedes or restricts the flow of liquid from the discharge of the impeller to the inlet thereof. This means that the losses in the impeller are reduced to a minimum as the impeller will be required to 15 handle but a limited amount of liquid.

It is also to be noted that there is considerable clearance between the sides of the impeller and the housing end walls 8 and 9. This permits of a desired amount of 20 axial adjustment of shaft 5 taking place; and such adjustments it will be noted do not affect the restricting clearances between the periphery of the impeller and the surrounding housing wall or those in the labyrinth 25 packing comprising rings 25 and 26 since such packing surfaces all extend in axial directions.

In Figs. 3 and 4 I have shown an arrangement similar to that of Figs. 1 and 2 except that the impeller side plates and the labyrinth packing are omitted and the same reference numerals have been applied to Figs. 3 and 4 as are used for corresponding parts in Figs. 1 and 2 except that the exponent "a" has been added. In this arrangement the impeller has a close running clearance with both the surrounding housing walls 10^a and with the end walls 8^a and 9^a, and thus serves to restrict the flow of 40 liquid from the exit of the impeller to the inlet thereof. In Fig. 3 the arrows indicate the direction of flow which the water takes in flowing from the discharge ends of the impeller vanes to the inlet ends. As 45 will be clear, this is a local circulation and, as indicated in the drawing, is greater on the low pressure side of the packing than it is on the high pressure side.

In accordance with the provisions of the 50 patent statutes, I have described the principle of operation of my invention, together with the apparatus which I now consider to represent the best embodiment thereof; but I desire to have it understood that the apparatus shown is only illustrative and that the invention can be carried out by other means.

What I claim as new and desire to secure by Letters Patent of the United States, is:

60 1. In a packing, the combination of a housing, an impeller therein having vanes, a rim which closes the peripheral ends of the vanes and has a close clearance with the adjacent wall of said housing, side plates

for said vanes, there being admission openings to the vanes at the centers of the side plates and discharge openings at the peripheries thereof, and conduit means for feeding sealing liquid to the packing. 65

2. In a packing, the combination of a 70 housing, an impeller therein having vanes, a rim which closes the peripheral ends of the vanes and has a close clearance with the adjacent wall of said housing, side plates for said vanes, said side plates being arranged to provide admission openings to the vanes at the centers of the side plates and discharge openings at the peripheries thereof, conduit means for feeding sealing liquid to said housing at the periphery of the impeller, and labyrinth packing means between the central portions of the side plates and the adjacent housing walls. 75

3. In a packing, the combination of a 80 housing, an impeller therein having vanes, a rim which closes the peripheral ends of the vanes and has a close clearance with the adjacent wall of said housing, side plates for said vanes, said side plates being arranged to provide admission openings to the vanes 85 at the centers of the side plates and discharge openings at the peripheries thereof, there being clearance spaces between the peripheries of said side plates and the housing wall through which said discharge openings communicate with the spaces at the sides of the impeller, and conduit means for feeding sealing liquid to said housing at the periphery of the impeller. 90

4. In a liquid seal packing, a housing, an 100 impeller therein having vanes on opposite sides, a rim which closes the radially outer ends of said vanes, side plates fastened to said vanes and terminating short of their radially inner and outer ends to leave admission and discharge openings for the vanes, and packing means for limiting the flow of sealing liquid from the discharge ends of the vanes to their inlet ends. 105

5. In a liquid seal packing, a housing, an 110 impeller therein which receives sealing liquid at its central portion and delivers it at the periphery, and labyrinth packing means which impedes the flow of liquid from the exit of the impeller to the inlet 115 thereof.

6. In a liquid seal packing, a housing, an 120 impeller therein which receives sealing liquid at its central portion and delivers it at the periphery, a side plate for said impeller, and interleaving packing rings carried by said side plate and the adjacent housing wall for impeding the flow of sealing liquid from the exit of the impeller to the inlet thereof. 125

In witness whereof, I have hereunto set my hand this 8th day of May, 1919.

JAMES WILKINSON.
